UNITED STATES PATENT OFFICE.

ARVID R. NELSON, OF MARATHON, IOWA.

END GATE AND MOUNTING.

Application filed July 29, 1922. Serial No. 578,433.

To all whom it may concern:

Be it known that I, ARVID R. NELSON, a citizen of the United States, and a resident of Marathon, in the county of Buena Vista 5 and State of Iowa, have invented a certain new and useful End Gate and Mounting, of which the following is a specification.

The object of my invention is to provide an end gate and mounting of simple, durable 10 and inexpensive construction.

More particularly, it is my purpose to provide such a device, which can be readily and easily mounted on a wagon box, the parts being so arranged that the end gate can be 15 removed from the mounting or assembled thereon easily and readily, and also so that the end gate may have swinging movement along a pivot line at its upper edge.

A further object is to provide suitable 20 means for locking the end gate in closed position.

With these and other objects in view, my invention consists in the construction, arrangement and combination of the various 25 parts of my device, whereby the objects contemplated are attained, as hereinafter more fully set forth, pointed out in my claims, and illustrated in the accompanying drawings, in which:

30 Figure 1 shows a top or plan view of an end gate and mounting embodying my invention, the rear portion of the wagon box being shown in dotted lines.

Figure 2 shows a rear elevation of the 35 same.

Figure 3 shows a side elevation of the left-hand mounting member.

Figure 4 shows a top or plan view of the same.

40 Figure 5 shows a side elevation of the left-hand mounting member.

Figure 6 shows a top or plan view of the same.

45 Figure 7 shows a side elevation of the left mounting member, which is secured to the end gate.

Figure 8 shows a similar view of the right corresponding member.

50 Figure 9 shows a detail, sectional view taken on the line 9—9 of Figure 2, illustrating part of the locking device.

Figure 10 shows a similar view taken on the line 10—10 of Figure 2.

Figure 11 shows a side elevation of a modi-

fied form of one of the mounting members; 55 and

Figure 12 shows a top view of the same.

In the drawings herewith, I have used the reference numeral 10 to indicate generally the bottom of a wagon bed or box, shown in 60 dotted lines in Figures 1 and 2.

The wagon box has the sides 11, which are provided at their rear ends with pairs of spaced upright cleats 12, which form guides for the end gate ordinarily used with the 65 wagon box.

My device consists of a pair of mounting members designed to be mounted on the wagon box, a pair of coacting mounting members designed to be mounted on the end 70 gate, an end gate, and a locking device arranged to coact with the various mounting members.

The mounting members, which are mounted on the wagon box are shown in two 75 forms, illustrated in Figures 3 and 5 and in Figures 11 and 12 respectively.

The forms for the mounting members shown in Figures 3 and 5 and also in Figures 4 and 6 are designed for use where 80 my device is used on the wagon box as built in the factory, with the cleats 12, while the form shown in Figures 11 and 12 is designed for use where the cleats are omitted, and my device is assembled as part of the wagon box 85 during manufacture in the factory.

The mounting members, which are mounted on the box, are made in rights and lefts.

In Figures 1, 2, 3 and 4 are illustrated the left-hand mounting member of the kind 90 used, where my device is put on the wagon box as an attachment. This mounting member comprises an upright strip or plate 13 designed to rest adjacent to the guide groove between the cleats 12 and having the laterally projecting upright member 14 arranged to be received in said guide groove. The member 14 may be channeled, as shown in Figure 3, to save weight.

On the plate or strip 13 is a forwardly 100 extending flange or lug 15 adapted to be bolted to the forward member of the pair of cleats, and an inwardly extending lug or the like 15^b adapted to serve as a stop for the end gate 16.

The plate 13 has a rearwardly extending lug or ear 17, which has a pin or pintle 18, shown in Figure 4, and in dotted lines in

Figures 2 and 3, substantially spaced from the stop lug 15^b.

The right-hand corresponding member is similarly constructed with an exception to be hereafter referred to, and the parts thereof are indicated by corresponding numerals with the addition of the letter "a."

The flange or lug 17 is at the top of the mounting member. At the bottom of the 10 mounting member is a rearwardly extending flange or plate 19, which has spaced openings 20 and 21 to receive the locking bar hereinafter referred to.

The right-hand mounting member under 15 consideration has a similar rearwardly extending flange 19^a with only one opening 20^a corresponding to the opening 20.

The mounting members heretofore described are assembled on the wagon box with the members 14 and 14^a received between 20 the pairs of cleats 12, as shown in Figure 1.

The mounting members on the wagon box may be secured to the wagon box and the forward cleats 12 by means of bolts extended through holes 22 in the flanges or 25 lugs 15 and 15^a.

The channel members 14 are closed at their upper ends by portions 23.

On the back of the end gate at each end 30 thereof is a mounting member.

The left-hand mounting member shown in Figures 1, 2 and 7 consists of an upright, rearwardly opening channel-shaped member 24 secured to the end gate member by means 35 of bolts or the like 25, and having at its upper end a heavier solid portion 26, through which extends from side to side, an opening 27 to receive the pin or pintle 18.

Extending inwardly from the portion 26 40 is a flange or lug 27^b, which may be secured to the end gate by means of a bolt 28.

In the lower end of the upright mounting member 24, the flanges are provided with openings 29 adapted in one position of the 45 end gate to register with the opening 20 to receive the locking bar hereinafter referred to.

The right-hand corresponding mounting member is similarly constructed with the exceptions hereinafter noted, the corresponding parts being indicated by similar numbers with the addition of the letter "a".

At the upper end of the right-hand member 24^a instead of the solid portion 26, there 55 is provided a hook member 30, which is designed to receive the pin 18^a. Adjacent to the hook member 30 and to the corresponding face thereof is an ear or lug 31, in which is a hole 32 to receive the inner end of the pin 60 18^a, which projects beyond the hook member 30, when the parts are assembled, and the sides of the wagon box are drawn together by means of the end gate rod 33.

In assembling the end gate on the wagon 65 box, the nut 34 on the end gate rod 33 is

loosened, so that the sides of the box can be pulled apart. The upright members 14 and 14^a are placed in position and the end gate is placed with the opening 27 receiving the pin 18.

The wagon box sides are then pulled apart until the pin 18^a can be made to clear the flange or ear 31 and to slip under the hook 30.

The wagon box sides are then drawn together by screwing up the nut 34 on the gate rod 33 for forcing the inner end of the pin 18^a into the opening 32.

The end gate will then have a pivotal mounting on the pins 18 and 18^a.

For locking the end gate member in closed position, I have provided the following means:

Mounted on the back of the end gate 16 is an upwardly opening channel-shaped 85 member 35, the flanges of which have oppositely projecting ears 36, which may be secured to the end gate by means of bolts or the like 37.

The channel-shaped member 35 is arranged in upright position (assuming the end gate to be upright), as shown in Figures 1, 2 and 10, and the rear wall thereof is provided with a longitudinally, elongated slot 38.

A bolt 39 is slidably received in the slot 38 and may have adjacent to its head on its inner end, a washer 40.

On the outer end of the bolt 39 is a nut 41. Mounted on the bolt 39 between the nut 41 100 and the channel-shaped member 35 are two locking bars 42 and 43.

The right hand-locking bar 42 extends in both directions from the bolt 39 and near its outer end is inclined inwardly, as at 44, and thence outwardly, as at 45.

The last-described portion 45 is slidably received in the opening 29^a, and when the locking bar 42 is in horizontal position, as illustrated in Figure 10, and the end gate is in closed position, it projects through the opening 20^a.

The locking bar 43 extends toward the member 24 and has a portion 46 spaced inwardly from the bar 42 when the bars 42 and 43 are in locking position to permit access to the fingers, so that the leftwardly projecting portion of the bar 42 may be conveniently grasped.

Near the outer end of the portion 46, 120 the bar 43 has a portion 47 arranged to snugly fit against the left-hand end of the bar 42, when the bars are in locking position.

A portion of the bar 43 extends forwardly, 125 as at 48, from the portion 47 and terminates in the laterally extending portion 49, which is slidably received in the opening 29, and is adapted to slide into and out of the openings 20 and 21.

In the portion 47 is a hole 50 and at the left-hand end of the bar 42 is a bolt or the like 51, having a rounded head 52 adapted to be received in the opening 50.

5 The locking bars 42 and 43 are somewhat resilient and are arranged so that the head 52 can be snapped into the opening 50 or can be pulled out of said opening.

On account of its rounded surface, the 10 head 52 can be readily slid out of the opening 50 when desired by grasping the bar 42 and pulling it upwardly.

In Figures 11 and 12, I have shown modified forms of those mounting members, 15 which are secured to the wagon bed.

The form of my device shown in Figures 11 and 12 is designed to be used where the cleats 12 are omitted.

These upright mounting members consist of the upright strip or the like 54 designed to be secured to the inner faces of the wagon bed sides and having other parts similar to those of the members 14 and 14^a.

In the practical use of my improved end 20 gate and mounting, the end gate is assembled on the wagon bed and swung to vertical position with the locking bars 42 and 43 raised until their central portions close the upper part of the channel-shaped 25 guide member 35, as illustrated by dotted lines in Figure 2.

The central or inner portions of the bars 42 and 43 are then forced downwardly, whereupon the end portions 45 and 49 will 30 slide into the openings 20^a and 20.

The head 52 can be snapped into the opening 50 and the end gate will then be locked in closed position.

When it is desired to discharge from the 40 wagon bed a load of shelled corn or oats or the like, the locking bars are pulled upwardly for sliding the bolt 39 upwardly in the guide slot 38 and withdrawing the outer ends of the locking bars from the openings 45 20^a and 20. Thereupon the lower part of the end gate can swing rearwardly and, the contents of the wagon box can be discharged at the rear end thereof.

Pivoted by means of a pin 55 at the lower 50 end of the member 24 is a chain 56, having at its free end a hook 57, which when the chain is not in use, may be hooked over a pin 58 in the member 24.

On the underside of the wagon box is a hook 60, shown in Figure 2, to which one link of the chain 56 may be secured for limiting the rearward outward swinging movement of the end gate 16.

Some changes may be made in the construction and arrangement of the parts of my improved device without departing from the real spirit and purpose of my invention, as set forth in the claims.

I claim as my invention:

65 1. A combination of an end wagon box

having a bottom and sides with a pair of mounting members adapted to be supported on said wagon box, an end gate, coacting mounting members supported on the end gate, the mounting members on the wagon box and the mounting members on the end gate being respectively provided with openings and pins for pivotally mounting the end gate on the wagon box, guide devices on the end gate, keeper portions on the wagon box and locking bars slidably mounted in said guides connected together for simultaneous operation for moving into or out of operative position with the relation to said keeper portions.

2. In a device of the class described, the combination of a wagon box having side members adapted to be spread apart somewhat from their normal position with an end gate mounting and an end gate, said end gate mounting comprising a pair of members arranged to be mounted on the sides of the wagon box and having inwardly projecting pins, end gate mounting members on the end gate near the ends thereof, one of said mounting members having a recess to receive one of said pins, the other of said mounting members having adjacent to the nearest wagon box side a hook for receiving one of said pins, and having projecting inwardly from said hook a portion provided with an opening, whereby by spreading the end gate sides apart, the end gate may be mounted with one pin projected into said first recess and the other pin received in said hook, and when the end gate sides are drawn together, the latter pin will be projected into the last-described opening, and means for locking the lower part of said end gate to the first described upright members.

3. In a device of the class described, a pair of upright members adapted to be mounted on the sides of a wagon box, said members having portions with holes therein, an end gate having mounting members thereon, pivoted at their upper ends on said first described members, said mounting members having at their lower parts openings adapted to register with said first-described openings when the end gate is in closed position, a vertical guide device on said end gate, a pair of locking bars pivoted together and slidably mounted on said guide devices, having their outer ends slidably mounted in the openings in said mountings and adapted when the locking bars are moved to a certain position to slide into the openings in said first described members.

4. In a device of the class described, the combination of a wagon box with upright members having openings near their lower portions, an end gate pivoted at its upper end to said upright members, keeper devices on said end gate having openings near

the lower edge thereof, a pivoted device 5 slidably mounted on said end gate, a pair of locking bars pivoted on said pivoted device, having their outer ends slidably extended through said keepers, said bars being arranged for a portion of their length in different planes to permit the convenient grasping of one of the bars, one of said

bars having a recess and the other being provided with a headed member to project 10 into said recess, said bars being resilient and being arranged to yieldingly hold the said headed device received in said recess when that position has been assumed.

Des Moines, Iowa, July 13, 1922.

ARVID R. NELSON.
